DENTAL TOPICAL ARCH TRAY

Alexander J. Drabkowski, 5565 Forman Drive,
Birmingham, Mich.

Filed Nov. 27, 1964, Ser. No. 82,848

Term of patent 14 years

(Cl. D24—1)

FIG. 1 is a top view of a dental topical arch tray embodying my new design; and

FIG. 2 is a rear elevational view taken on the line 2—2 of FIG. 1; and

FIG. 3 is a side elevational view taken on the line 3—3 of FIG. 1; and

FIG. 4 is a front elevational view; and

FIG. 5 is a bottom view; and

FIG. 6 is a cross sectional view taken on the line 6—6 of FIG. 1; and

FIG. 7 is a cross sectional view taken on the line 7—7 of FIG. 1.

I claim:

The ornamental design for a dental topical arch tray, substantially as shown.
